DESIGN FOR A STOVE BY N. P. RICHARDSON.

Des. 363

P. P. Richardson of Portland, Maine.
Letter Patent No. 363 Dated April 1, 1851.

The Schedule referred to in these Letters Patent and making part of the same.

To all Persons to whom these Presents shall come:
Be it known,

that I, N. Putnam Richardson, of Portland, in the County of Cumberland, and State of Maine, have invented a new and useful, ornamental design for an air tight stove, and I do hereby declare that the same is fully described and represented in the following specification and accompanying drawings, letters, figures and references thereof.

In representing my new design, I have preferred to exhibit the ornamental appearance of each part of the stove, except the upright sides, or elliptic drum, which rests on the bottom plate, (seen in Fig. 1,) and receives on its top, the top plate, seen in Figure 3, the said drum being made in the usual way.

Figure 1 of the drawings, denotes the design of the bottom plate. Fig. 2 is a central and transverse section of it — Fig. 3 exhibits the design of the top plate and cover — Fig. 4 being a cross section thereof. Fig. 5 is a representation of the ornamental design of the oven door; while Fig. 6 is a central cross section of it. Fig. 7 is a view of the design for the fuel door. Fig. 8 is a cross section of the said fuel door. Fig. 9 is an external view of one of the feet of the stove.

What I claim as my invention, is the ornamental design of the air tight stove, substantially as exhibited in the drawings, and as above described.

In testimony whereof, I have hereunto set my signature, this twenty-seventh day of November, A.D. 1850.

Witnesses:

Edward Fox
